COMBINED HITCHING DEVICE AND GUARD
FOR TRACTORS OR THE LIKE

Menne S. Stoltzfus, Cochranville, Pa.

Application June 16, 1949, Serial No. 99,532

2 Claims. (Cl. 280—33.44)

1

My invention relates to a combined hitching device and guard for tractors or the like.

An important object of the invention is to provide a device of the above mentioned character which is extremely simple in construction, strong and durable.

A further object of the invention is to provide a device of the above mentioned character so constructed that the pull when the unit is used as a hitching device is transmitted directly to the attaching lugs.

In the accompanying drawings, forming a part of this application, and in which like numerals are employed to designate like parts throughout the same,

Figure 1 is a side elevation of a combined hitching device and guard embodying my invention, showing the same applied to the front end of a tractor.

Figure 2 is a plan view of the same.

Figure 3 is a front elevation of the combined hitching device and guard removed.

Figure 4 is a vertical longitudinal section taken on line 4—4 of Figure 3.

Figure 5 is a horizontal section taken on line 5—5 of Figure 3.

Figure 6 is a rear elevation of the combined hitching device and guard removed, and

Figure 7 is a vertical section taken on line 7—7 of Figure 5.

In the drawings, where for the purpose of illustration is shown a preferred embodiment of my invention, the numeral 10 designates the chassis of a tractor provided at its front end with the usual radiator 11. This tractor may be of the type employed for agricultural purposes.

My combined hitching device and guard is designated as a whole by the numeral 12 and is arranged vertically in advance of the radiator 11, as shown. The device comprises an elongated rectangular frame 13 including sides 14, a top 15 and bottom 16. These elements are preferably formed of a steel bar square in cross-section. The top 15 and bottom 16 are connected with the sides 14 by rounded corners 17. The top 15 and bottom 16 are longitudinally curved in a horizontal plane, whereby the entire guard is cylindrically curved, with its convex face arranged forwardly. Arranged within the frame 13 are vertical spaced bars 18, preferably formed of steel and preferably square in cross-section. These bars 18 are parallel with the sides 14 and are rigidly and integrally connected with the top and bottom by welding. It is thus seen that I have provided a guard element which is cylindri-

2

cally curved and which is extremely stiff and strong.

Arranged near, above, and spaced from the bottom 16, and rearwardly of the sides 14, are lower attaching lugs 19, preferably formed of steel. These lugs are rigidly and integrally connected with the sides 14 by welding. The lugs 19 are in horizontal alignment and have horizontally spaced apertures 20. The lugs 19 are positioned adjacent to the inner edges of the sides 14, Figure 5, and have their forward ends inwardly beveled, as at 19' to provide abutting faces between the sides 14 and lugs, and to facilitate the proper welding of the lugs to the sides 14.

The numeral 21 designates a horizontal bridge, preferably formed of steel. This bridge is wide and has a longitudinally curved convex forward edge 22. The rear edge 22' of the bridge is straight, as shown. The bridge has its ends arranged in abutting relation with the inner faces of the lugs 19, and such ends are rigidly and integrally connected with the lugs 19 by welding, as indicated at 23. The curved edge 22 abuts the rear faces of the sides 14 and the rear faces of the bars 18 and is integrally and rigidly secured thereto by welding, as shown at 24 and 25. The bridge 21 is wide and strong and is provided at its longitudinal center with an opening 26 for receiving a pull element, such as a chain or cable. Upstanding diagonal bars or braces 27 are provided, and have their upper ends 28 beveled and integrally welded to the rear faces of the sides 14, Figure 4. The lower ends 29 of the braces 27 are integrally welded to the top edges of lugs 19, as shown, and the braces 27 are in vertical alignment with the lugs.

The device is applied to the forward end of the chassis 10 by horizontal bars 30, secured to the lugs 19 by bolts 31 which pass through the spaced apertures 20. The horizontal bars 30 are attached to the chassis 10 by bolts 32. The horizontal bars 30 are disposed laterally outwardly of the lugs 19, and have their forward ends disposed rearwardly of the sides 14, Figure 5, so that they contact therewith and prevent any swinging movement of the guard 12 with relation to the chassis.

In view of the foregoing description, it is obvious that I have provided a guard element which is unitary, rigid, and strong, and which has a forward convex face which will deflect obstructions laterally. When the device is used to pull a load, a chain or the like is secured in the opening 26 of the bridge 21 and the load is trans-

mitted directly to the lugs 19 through the bridge 21.

It is to be understood that the form of my invention herewith shown and described is to be taken as a preferred embodiment of the same, and that various changes in the shape, size, and arrangement of parts, may be resorted to without departing from the spirit of my invention or the scope of the subjoined claims.

Having thus described my invention, I claim:

1. A combined hitching device and guard, comprising an upstanding cylindrically curved guard element including a frame embodying upstanding sides and a top and bottom, the top and bottom being longitudinally curved, upstanding bars within the frame and rigidly secured to the top and bottom, lower attaching lugs arranged near the bottom and rigidly secured to the sides and extending rearwardly of the sides, an a substantially horizontal wide bridge having a forward longitudinally curved face which abuts the upstanding bars and is integrally connected therewith and ends which abut the inner faces of the attaching lugs and are integrally connected therewith, said bridge having an opening near its longitudinal center.

2. A combined hitching device and guard, comprising an upstanding cylindrically curved guard

element including a frame embodying upstanding sides and a top and bottom, the top and bottom being longitudinally curved, upstanding bars within the frame and rigidly secured to the top and bottom, lower attaching lugs arranged near the bottom and disposed in abutting relation with the rear faces of the sides and integrally secured to such rear faces, a substantially horizontal wide bridge having a forward longitudinally curved face which abuts the upstanding bars and is integrally connected therewith and ends which abut the inner faces of the attaching lugs and are integrally connected therewith, said bridge having an opening near its longitudinal center, and diagonal braces having their lower ends connected with the lugs and their upper ends connected with the sides of the guard.

MENNO S. STOLTZFUS.
